BARBECUE CONDIMENT DISPENSER

Paul G. Mathes, Pittsfield, Ill.

Application October 8, 1958, Serial No. 52,910

Term of patent 14 years

(Cl. D44—22)

Fig. 1 is a front elevational view of the barbecue condiment dispenser embodying my new design;

Fig. 2 is a side elevational view of the same;

Fig. 3 is a rear elevational view of the same;

Fig. 4 is a fragmentary front elevational view of the same and enlarged to show the dispensing head thereof;

Fig. 5 is a top plan view of the dispenser as illustrated in Fig. 2; and

Fig. 6 is a bottom plan view of said dispenser.

The dominant features of the design reside in the portions shown in full lines.

I claim:

An ornamental design for a barbecue condiment dispenser, substantially as shown and described.
